UNITED STATES PATENT OFFICE.

FRANCES KIERAN, OF NEW YORK, N. Y.

DESIGN FOR A RIBBON.

No. 38,318.

Specification for Design.

Patented Nov. 20, 1906.

Application filed October 9, 1906. Serial No. 338,194. Term of patent 3½ years.

To all whom it may concern:

Be it known that I, FRANCES KIERAN, of New York, in the county of New York and State of New York, have invented a new, original, and ornamental Design for Ribbons, of which the following is a specification, reference being had to the accompanying drawing, forming part hereof.

The figure is a plan view of the ribbon, showing my design.

I claim—

The ornamental design for a ribbon, as shown.

FRANCES KIERAN.
